UNITED STATES PATENT OFFICE

117,046

DESIGN FOR A BUILDING

Charles J. Matuella, Hazleton, Pa.

Application July 27, 1939, Serial No. 86,275

Term of patent 14 years

To all whom it may concern:

Be it known that I, Charles J. Matuella, a citizen of the United States, residing at Hazleton, in the county of Luzerne and State of Pennsylvania, have invented a new, original, and ornamental Design for a Building, of which the following is a specification, reference being had to the accompanying drawings, forming part thereof.

I claim:

The ornamental design for a building, as shown.

CHARLES J. MATUELLA.
